UNITED STATES PATENT OFFICE.

HARRY G. BOARDMAN, OF CHICAGO, ILLINOIS, ASSIGNOR TO AUTOMATIC BASEBALL CO.
OF ILLINOIS, OF CHICAGO, ILLINOIS, A CORPORATION OF ILLINOIS.

POWER-DRIVEN BASE-BALL PITCHER.

1,213,577.

Specification of Letters Patent. Patented Jan. 23, 1917.

Application filed May 31, 1916. Serial No. 100,986.

To all whom it may concern:

Be it known that I, HARRY G. BOARDMAN, a citizen of the United States, residing at Chicago, in the county of Cook and State of Illinois, have invented a new and useful Power-Driven Base-Ball Pitcher, of which the following is a specification.

My invention relates to baseball pitchers, and the principal object of the invention is to provide a pitcher which will be power-driven, and which will pitch balls continuously at regular intervals, this pitcher being located in a screened inclosure having a sloping floor so arranged as to return the balls to the pitcher.

A second object of the invention is to provide ball feeding means for such a baseball pitcher, these feeding means being arranged to receive the balls from the sloping floor, and to feed them to the pitcher from either side.

A third object of the invention is to provide a pair of power driven baseball pitchers which are arranged side by side, and served by the same feeding means, these pitchers being combined with mechanism whereby either pitcher may be run alone, and whereby the feeding means will in that case serve the operating pitcher from either side.

A fourth object of the invention is to provide a mechanism for actuating the feeding means which will be driven twice as fast when both pitchers are operating as when only one is operating.

A fifth object of the invention is to provide in connection with the feeding means an overflow trough which will receive any balls in excess of the requirements of the pitcher, passing these balls back to the feeding means in case of an over-supply of balls.

A sixth object of the invention is to provide a pitcher which can be made to throw a ball to either side of a narrow court so as to serve either a right or a left hand batter in a small space.

A seventh object of the invention is to provide means for varying the tension on the control spring so as to vary the speed of the ball thrown.

Further objects and advantages will be made evident hereinafter.

Referring to the drawings, which are for illustrative purposes only: Figure 1 is a plan view of a court in which a pair of plan view of a court in which a pair of pitchers are placed. Fig. 2 is a sectional

elevation of the apparatus shown in Fig. 1. Fig. 3 is a side elevation partly in section of one of the pitchers. Fig. 4 is a plan view of a pair of pitchers. Fig. 5 is a rear elevation of a portion of the feeding means and connections therebetween. Fig. 6 is an elevation partly in section of the lower portion of a pitcher, and its connected parts. Fig. 7 is an elevation of a portion of the drive for the feeding means. Fig. 8 is a partial section through the air dash-pot.

In my invention, a closed court 11 is provided, this court having a floor 12 which slopes back to a feeding trough 13. A playing field 14 is secured in the rear of the court, being fastened by pulleys to the top and back of the court, and being secured to the floor 12 at a point just behind the feeding trough 13. A pair of pitchers 15 and 16 are secured on the floor 12 just in front of the feeding trough 13, these pitchers being controlled by operators located on platforms 17 at the extreme front of the court. The court 11 is entirely inclosed with canvas or netting, or both, so that there is no possibility of a ball being batted outside the court. A rear protector 18, and a front protector 19 are provided to protect the pitchers 15 and 16 from batted balls.

The pitchers 15 and 16 are practically duplicates of each other, except that they are arranged for right and left hand operation as will be readily understood from the drawings. Each of the pitchers consists of a base 20 on which is mounted a cast iron standard 21, this standard being of U-section with a web 22 extending across the forward end thereof. Secured to the web 22 by means of bolts 23 is a gear frame 24, this gear frame having bearings therein in which a gear shaft 25 is free to turn. Secured on the gear shaft 25 is a worm gear 26, this worm gear meshing in and being driven by a worm 27 which is secured on a shaft 28 carried in bearings on the gear frame 24. The shaft 28 is driven through a coupling 29 by an electric motor 30. The gear 26 is provided with a crank pin 31 on which a roller 32 is free to turn, the roller 32 fitting into and sliding freely in a slot 33 which is formed in a crank lever 34. The slot is so shaped that that portion contained in the arc $a-b$ of Fig. 3 is concentric with the center of the shaft 25 when the roller 32 is located therein, the portion

of the slot 33 in the arc *a*—*b* being provided for the purpose of allowing the gear 26 to rotate without actuating the crank lever 34, this portion of the slot being called 5 hereinafter the dwell. The remainder of the slot is shaped as shown in the drawing for purposes that will be further described hereinafter. The crank lever 34 is pivoted on an eccentric portion of a pin 35, this 10 pin having ends 36 which are eccentric with the portion 35, and these ends 36 being journaled in and turning freely in an eccentric bearing bracket 37 which is secured to the web 22 by means of bolts 38. Secured on 15 one end of the pin 36 is an eccentric lever 39, this lever being connected through a rod 40 with a bell crank 41 which turns on a pin 42 secured in a bracket 43 formed on the base 20. The other arm of the bell crank 41 is connected through a rod 44 with an operating lever 45, each of the operating levers 45 being located on one of the platforms 17 within easy reach of the operators.

20 A clevis bar 50 is mounted in pins 51 on the upper end of the crank lever 34, and a spring 52 is secured in a clevis 53 which is pivoted on pins 54 formed on the clevis bar 50. The opposite end of the spring 52 is secured to a clevis 55 which is pivoted on a pin 56 passing through the lower end of a throwing arm 57. The throwing arm 57 is in turn pivoted on a pin 58 carried in a throwing arm bracket 59. Secured to the upper end of the throwing arm 57 is a throwing finger 60, this throwing finger being preferably formed of stiff wire bent in U-shape of a sufficient size to form a trough, and in which a baseball such as that shown at 61 can readily roll. Secured on the upper end of the throwing arm 57 between the two sides of the finger 60 is a hook 62, this hook being engaged by a latch 63 which is pivoted on a pin 64 carried in a latch bracket 65, the latch bracket 65 being secured on a web 66 of the throwing arm bracket 59. A compression spring 67 tends to hold the latch 63 in engagement with the hook 62 thereby restraining the throwing arm 57 against the tension of the spring 52. A trigger 68 is pivoted on a pin 69 carried on the latch bracket 65, one end of this trigger extending up between the two arms of the throwing finger 60 in such a position that it will be hit by the ball 61 as it rolls downwardly over the finger, and the other end 70 of the trigger 68 being so placed that it will throw the latch 63 out of engagement with the hook 62 when the trigger is struck by the ball.

Pivoted on trunnions 75, carried on an extension 76 of the throwing arm bracket 59, is a dash-pot 77, this dash-pot having a piston 78 sliding therein. The piston 78 is provided with a piston rod 79 which is pivoted on a pin 80 carried in ears 81

formed on the top of the throwing arm 57. The piston 78 is provided with a plurality of small holes 85, these holes being closed by a valve washer 86, this valve washer 86 having a very limited movement on the piston rod 79, and being so arranged that it closes the holes 85 during the throwing operation of the pitching arm, backing off and opening the holes as the pitching arm is returned to its initial position as will 70 hereinafter be more fully described. A plurality of needle valves 87 are provided, these valves communicating through openings 88 with the outer air, and being adapted to be closed to provide a greater or less 75 cushioning effect as may be desired.

The throwing arm bracket 59 is secured by means of pins 90 to a vertical shaft 91 which turns freely in projections 92 formed on the web 22, this shaft extending down 80 and terminating in a crank 93, this crank having a pin 94 which extends out and is engaged by a spiral cam 95, this spiral cam being secured on an adjusting shaft 96. Each of the adjusting shafts 96 extends 90 forward and is connected to an adjusting lever 97, each of which is placed on one of the platforms 17 within convenient reach of the operator.

Secured on the inner side of the web 22 is 95 an adjustable throat 100, this throat being provided with slots 101 through which bolts 102 pass so that it can be moved up or down as may be desired. The balls are elevated by means of a chain 105, this chain 100 carrying buckets 106 which are of the form shown in Fig. 3. The chain 105 passes over a head sprocket 107, this sprocket turning freely on a head shaft 108 which may be adjusted up or down in slots 109 formed in 105 head sprocket projections 110 of the standard 21, this adjustment of the shaft 108 being provided for the purpose of taking up the wear of the chain 105. Located on brackets 111 are idler wheels 112 which tend 110 to hold the chain in the position shown in Fig. 3, and turning freely in extensions 113 of the standard 21 is a foot shaft 114, this foot shaft being rigidly secured to a ratchet wheel 115, and a sprocket wheel 116, the 115 chain 105 passing over the sprocket 116 and being driven thereby. The ratchet 115 is provided with teeth 117 which are engaged by a pawl 118 carried on a pawl arm 119 which turns freely on the shaft 114. The 120 pawl arm 119 is driven through a rod 120 from a pin 121 secured on the crank lever 34, the rod 120 passing through a block 122 which is swiveled on the pin 121. A compression spring 123 surrounds the rod 120 125 and presses at one end on a nut 124, and at the other end on the block 122. A spring 125 surrounds the shaft 114, one end being secured in the extension 113, and the other end being secured to the arm 119 in such a 130

manner as to rotate it in a counter-clockwise direction as viewed in Fig. 3 against the tension of the spring 123.

Secured to the extensions 113 is a trough 126, this trough being cut away at 127 and 128 as shown in Fig. 4 to allow the bucket 106 to pass therethrough. An auxiliary trough 129 is formed on the rear of the trough 126, this auxiliary trough being higher and being inclined as shown in Fig. 5 so as to feed any balls back in case of a surplus of balls accumulating in the trough 126, such surplus of balls being raised by the pressure of the incoming balls into the trough 129.

Belts 130 and 131, passing over pulleys 132 and 133, pass through the trough 13. The pulleys 132 and 133 are secured to shafts 134 and 135 respectively, to which are also secured sprockets 136 and 137. A chain 138 passes over these sprockets as shown in Fig. 5, and also over idler sprockets 139 and 140, this chain being driven by a driving sprocket 141 carried on a shaft 142. The shaft 142 extends inwardly between the pitchers, being journaled in a feeder shaft bracket 150. A ratchet wheel 151 is secured to the forward end thereof, this ratchet wheel being engaged by racks 152 and 153 which slide in guides 154, and which are driven by links 155 from crank pins 156 carried on cranks 157 which are secured to the shafts 25. Each of the racks 152 and 154 is held in engagement with the wheel 151 by a flat spring 158.

The method of operation is as follows: The motor 30 being energized by electric current from any suitable means, the gear 26 is driven by the worm 27 in a clockwise direction as viewed in Fig. 3. At the instant shown in that drawing one of the balls has been delivered by the elevator, as will hereinafter be described, this ball passing over the adjustable throat 100 onto the finger 60 over which it passes. This movement of the ball 61 from the position shown at "A" in Fig. 3 to the position shown at "B" in Fig. 3 taking place during the time that the roller 32 is in the dwell of the slot 33. During this time, although the gear 26 has moved through an arc equal to the angle $a-b$, there has been no change in the position of the crank lever 34. The tension on the spring 52 has thereby been maintained during this period. The ball 61 strikes against the end of the trigger 68, causing the latch 63 to release the hook 62, and the throwing arm 57 is rotated in the direction of the arrow "X" of Fig. 3, the ball 61 being thrown forward by the finger 60, this ball 61 rolling forward by the finger as the arm 57 rotates and being discharged toward the batter. As the throwing arm 57 moves forward, the dashpot 77 serves to check the final force of its movement, the degree of this checking action

being regulated by the valves 87. A further movement of the gear 26 releases the tension on the spring 52 by turning the crank lever 34 and the throwing arm 57 is then returned to its initial position, being latched in place by the latch 63 catching on the hook 62. A further movement of the gear 26 resets the spring 52 and the operation is repeated.

During one revolution of the gear 26 the ratchet arm 119 is moved through an angle slightly greater than 90° . This movement of 90° of the arm 119 is transmitted to the ratchet wheel 115 through the pawl 118 so that the ratchet wheel 115, the shaft 114, and the sprocket 116 are turned 90° for each revolution of the gear 26. The sprocket 116 and the chain 105 are so proportioned, and the buckets 106 are so located, that one of the balls 61 is delivered into the position "A" for each revolution of the gear 26, the actual delivery of the ball to the throwing finger 60 taking place while the roller 32 is in the dwell of the slot 33.

The movement of the shaft 25 is transmitted through the crank 157 and the crank pins 156 to one of the racks 152 or 153, these racks having oppositely inclined teeth, and being so arranged that the teeth of the ratchet wheel 151 are passed thereby if for any reason the racks 152 and 153 are stationary. The result is that either of the shafts 25 will drive the shaft 142, or if both the shafts 25 are rotated the shaft 142 will be driven at twice the rate that it would be were only one of the shafts 25 rotated, the rotation of the shaft 142 actuating the chain 138 through the sprocket 141, and the pulleys 142 and 143 are turned in such a way as to move the upper surface of the belts 130 and 131 toward the center of the pitcher. Any balls carried by the belts are therefore delivered onto the trough from which they are carried upwardly by the buckets 106. Any crowding of the balls in the trough tending to lift same being provided for by the balls being caught by the overflow trough 129, and returned to the belts 130 and 131.

It is desirable in many cases to install a pair of pitchers in a narrow space such as an ordinary city storeroom, and it is further desirable to be able to arrange either pitcher to deliver a ball in a convenient position to be struck by either a right or a left hand batter. This can be accomplished by a rotation of the whole pitcher, but I prefer to move only the pitching arm bracket 59 which I accomplish by a rotation of the shaft 91 by means of the crank 93 and the spiral cam 94, this rotation being accomplished by means of the shaft 96. It is thus possible for an operator on either of the platforms 17 by operating the shaft 96 to turn either of the pitchers to throw to the right or the left, or to any intermediate position.

diate position in the court to suit the convenience of the batter. It is further desirable to allow the operator of the machine to vary the speed of the pitched ball, and 5 this is readily accomplished by varying the fulcrum of the lever 34, this being accomplished by turning the eccentric 35 through the rod 40, the bell crank 41, and the rod 44. It is thus possible for the operator by a 10 manipulation of the lever 34 to cause the pitcher to throw either a fast or a slow ball.

In actual operation a sufficient supply of balls is provided to allow for some storage and for filling all of the buckets 106 which 15 are ever in action at one time. The motor is so regulated and the parts are so proportioned that the balls are thrown at sufficiently long intervals to suit the convenience of the batter. It is further possible 20 to operate either one or both pitchers, and to feed the balls twice as fast when both pitchers are operating as when one pitcher is operating.

I claim as my invention:

25 1. A pair of baseball pitchers, two lifting means each adapted to deliver balls to one of said pitchers, horizontal means for feeding balls to said lifting means, driving means for each lifting means, and means by 30 which either or both of said driving means can drive said horizontal means, said horizontal means being driven twice as fast by both of said driving means as it is when driven by either alone.

35 2. In a baseball pitcher, a lifting means, a horizontal trough through which balls are delivered to said lifting means, and an overflow trough for receiving excess balls from near the center of said horizontal trough 40 and delivering them to a point near the beginning of said horizontal trough.

45 3. In a baseball pitcher, a lifting means, a horizontal trough through which balls are delivered to said lifting means, and a belt driven from said baseball pitcher for delivering balls to said trough.

50 4. In a baseball pitcher, a sloping floor, a horizontal trough located in the low portion of said floor, a second horizontal trough 55 for said pitcher, two belts extending in either direction from said pitcher and each delivering balls to said second trough, and means by which both of said belts are driven by said pitcher.

55 5. In a baseball pitcher, a standard; a bracket attached to said standard; a throwing arm pivoted in said bracket; a tension spring attached at one end to one end of said throwing arm; a crank lever pivoted on said 60 standard and having one end of said tension spring attached to one end thereof; and motor driven means for actuating the other end of said crank lever.

65 6. In a baseball pitcher, a standard; a bracket attached to said standard; a throw-

ing arm pivoted in said bracket; a tension spring attached at one end to one end of said throwing arm; a crank lever pivoted on said standard and having one end of said tension spring attached to one end thereof, 70 said crank lever having a slot formed therein; a gear shaft; a gear on said gear shaft; power means for driving said gear; and a crank pin secured on said gear, engaging said slot, and actuating said crank lever. 75

7. In a baseball pitcher, a standard; a bracket attached to said standard; a throwing arm pivoted in said bracket; a tension spring attached at one end to one end of said throwing arm; a crank lever pivoted on said standard and having one end of said tension spring attached to one end thereof, 80 said crank lever having a slot formed therein; a gear shaft; a gear on said gear shaft; power means for driving said gear; and a crank 85 pin secured on said gear, engaging said slot, and actuating said crank lever, a portion of said slot being curved on an arc having the same mean radius as said crank pin so that said pin can move in said curved portion of 90 said slot without moving said crank lever.

8. In a baseball pitcher, a standard; a bracket pivoted about a vertical axis to said standard; means by which an operator can swing said bracket about said axis; a throwing arm pivoted in said bracket; a tension spring attached at one end to one end of said throwing arm; a crank lever pivoted on said standard and having one end of said tension spring attached to one end thereof; and motor driven means for actuating the other end 95 of said crank lever. 100

9. In a baseball pitcher, a standard; a bracket pivoted about a vertical axis to said standard; means by which an operator can swing said bracket about said axis; a throwing arm pivoted in said bracket; a tension spring attached at one end to one end of said throwing arm; a crank lever pivoted on said standard and having one end of said tension spring attached to one end thereof, 105 said crank lever having a slot formed therein; a gear shaft; a gear on said gear shaft; power means for driving said gear; and a crank pin secured on said gear, engaging said slot, 110 and actuating said crank lever.

10. In a baseball pitcher, a standard; a bracket pivoted about a vertical axis to said standard; means by which an operator can swing said bracket about said axis; a throwing arm pivoted in said bracket; a tension spring attached at one end to one end of said throwing arm; a crank lever pivoted on said standard and having one end of said tension spring attached to one end thereof, 120 said crank lever having a slot formed therein; a gear shaft; a gear on said gear shaft; power means for driving said gear; and a crank pin secured on said gear, engaging said slot, 125 and actuating said crank lever.

a portion of said slot being curved on an arc having the same mean radius as said crank pin so that said pin can move in said curved portion of said slot without moving said

5 crank lever.

11. In a baseball pitcher, a standard; a bracket attached to said standard; a throwing arm pivoted in said bracket; a tension spring attached at one end to one end of 10 said throwing arm; a crank lever pivoted on said standard and having one end of said tension spring attached to one end thereof; eccentric means by which an operator can vary the position of the pivot of said crank 15 lever with relation to said standard to increase or diminish the tension of said spring; and motor driven means for actuating the other end of said crank lever.

12. In a baseball pitcher, a standard; a bracket attached to said standard; a throwing arm pivoted in said bracket; a tension spring attached at one end to one end of 20 said throwing arm; a crank lever pivoted on said standard and having one end of 25 said tension spring attached to one end thereof; eccentric means by which an operator can vary the position of the pivot of said crank lever with relation to said standard to increase or diminish the tension of 30 said spring; said crank lever having a slot formed therein; a gear shaft; a gear on said gear shaft; power means for driving said gear; and a crank pin secured on said gear, 35 engaging said slot, and actuating said crank lever.

13. In a baseball pitcher, a standard; a bracket attached to said standard; a throwing arm pivoted in said bracket; a tension spring attached at one end to one end of 40 said throwing arm; a crank lever pivoted on said standard and having one end of said tension spring attached to one end thereof; eccentric means by which an operator can 45 vary the position of the pivot of said crank lever with relation to said standard to increase or diminish the tension of said spring, said crank lever having a slot formed therein; a gear shaft; a gear on said gear shaft; power means for driving said gear; and a 50 crank pin secured on said gear, engaging said slot, and actuating said crank lever, a portion of said slot being curved on an arc 55 having the same mean radius as said crank pin so that said pin can move in said curved portion of said slot without moving said crank lever.

14. In a baseball pitcher, a standard; a bracket pivoted about a vertical axis to said standard; means by which an operator

can swing said bracket about said axis; a throwing arm pivoted in said bracket; a tension spring attached at one end to one end of said throwing arm; a crank lever pivoted on said standard and having one end of said tension spring attached to one 60 end thereof; eccentric means by which an operator can vary the position of the pivot of said crank lever with relation to said standard to increase or diminish the tension of said spring; and motor driven means 65 for actuating the other end of said crank lever.

15. In a baseball pitcher, a standard; a bracket pivoted about a vertical axis to said standard; means by which an operator 70 can swing said bracket about said axis; a throwing arm pivoted in said bracket; a tension spring attached at one end to one end of said throwing arm; a crank lever pivoted on said standard and having one 75 end of said tension spring attached to one end thereof; eccentric means by which an operator can vary the position of the pivot of said crank lever with relation to said standard to increase or diminish the tension 80 of said spring, said crank lever having a slot formed therein; a gear shaft; a gear on said gear shaft; power means for driving said gear; and a crank pin secured on said gear, 85 engaging said slot, and actuating said crank lever.

16. In a baseball pitcher, a standard, a bracket pivoted about a vertical axis to said standard; means by which an operator can 90 swing said bracket about said axis; a throwing arm pivoted in said bracket; a tension spring attached at one end to one end of said throwing arm; a crank lever pivoted on said standard and having one end of said tension spring attached to one end thereof; eccentric means by which an operator can 95 vary the position of the pivot of said crank lever with relation to said standard to increase or diminish the tension of said spring, 100 said crank lever having a slot formed therein; a gear shaft; a gear on said gear shaft; power means for driving said gear; and a crank pin secured on said gear, 105 engaging said slot, and actuating said crank lever, a portion of said slot being curved on an arc 110 having the same mean radius as said crank pin so that said pin can move in said curved portion of said slot without moving said crank lever.

In testimony whereof, I have hereunto 115 set my hand at Olympia, Wash., this 24th day of April, 1916.

HARRY G. BOARDMAN.
